UNITED STATES PATENT OFFICE.

THOMAS H. HARTMAN, OF WILLIAMSPORT, PENNSYLVANIA.

HAMMOCK.

SPECIFICATION forming part of Letters Patent No. 374,472, dated December 6, 1887.

Application filed August 20, 1887. Serial No. 247,452. (No model.)

To all whom it may concern:

Be it known that I, THOMAS H. HARTMAN, a citizen of the United States, residing at Williamsport, in the county of Lycoming and State 5 of Pennsylvania, have invented certain new and useful Improvements in Hammocks; and I do hereby declare the following to be a full, clear, and exact description of the invention, such as will enable others skilled in the art to 10 which it appertains to make and use the same.

This invention relates to hammocks, and it has for its object to provide a hammock of wooden slats so connected as to yield readily to pressure or conform to the body of the person thereon; and it consists of the parts and 15 combinations of parts, hereinafter described and claimed.

In the accompanying drawings, forming a part of this specification, Figure 1 is a perspective view of my improved hammock, and Fig. 2 a perspective view of one of the slats.

Similar letters refer to similar parts in both views.

A represents the end slats, which, for the 25 sake of finish, are somewhat wider than the slats B, forming the body of the hammock, and are finished on their outer edges with scroll-work, as shown. The inner edges of the slats A and both edges of the slats B are rounded, 30 as clearly shown in the drawings. The purpose of thus rounding the edges of the slats is to permit of their easily yielding or turning edge against edge when folded or rolled, or when the hammock is in use. This construction of the slats also prevents the clothing or 35 flesh of the user being caught or pinched between the slats, and permits of the rolling of the hammock in a compact form for storage or transportation. Through each of the slats

near their ends a perforation, c, is formed, 40 through which cable wire or rope a is passed and the ends thereof knotted or otherwise secured to a ring, b, at each end of the hammock, to which wire or rope is secured for the purpose of swinging the hammock. Thus it will 45 be seen that I provide a flexible hammock, either side of which may be used, as the slats are straight, and that it may be rolled with either side in, as desired, while it may be cheaply constructed and is very durable. 50

I am aware that chair bottoms and backs have been made of slats having perforations near their ends through which wires are passed and having thimbles or washers between each pair of slats, and also that bottoms have been 55 made of strips of wood having their upper surface rounded and having strips of metal passed transversely through said strips of wood, and I do not desire to be understood as claiming such construction.

Having thus described my invention, what I claim as new, and desire to secure by Letters Patent, is—

A flexible or self-conforming hammock consisting of the end slats, A, having one of their 65 edges rounded, the body-slats B, having both their edges rounded and having the perforations c formed therethrough at right angles to the longitudinal axes of the slats, the cable wire or rope a, passed through said perforations, and the rings b, secured to the ends of said wire or rope, substantially as described. 70

In testimony whereof I affix my signature in presence of two witnesses.

THOMAS H. HARTMAN.
